UNITED STATES PATENT OFFICE.

JAMES C. ASKREN, OF BEDFORD, IOWA.

BALANCED SLIDE-VALVE.

SPECIFICATION forming part of Letters Patent No. 411,754, dated September 24, 1889.

Application filed December 21, 1888. Serial No. 294,320. (No model.)

To all whom it may concern:

Be it known that I, JAMES C. ASKREN, a citizen of the United States; residing at Bedford, in the county of Taylor and State of Iowa, have invented a new and useful Improvement 5 in Balanced Slide-Valves, of which the following is a specification.

My invention relates to an improvement in balanced slide-valves for locomotives and 10 other reciprocating steam-engines; and it consists in the peculiar construction and combination of devices, that will be more fully set forth hereinafter, and particularly pointed out in the claim.

15 In the drawings, Figure 1 is a side elevation of a valve embodying my improvements, showing the same arranged in the steam-chest of an engine, the said chest being indicated by dotted lines. Fig. 2 is a vertical sectional view of my improved valve. Fig. 3 is a top plan view of the same. Fig. 4 is a detail perspective view of the hood. Fig. 5 is a detail sectional view taken on the line $x-x$ in Fig. 3.

20 A represents the valve, which is located in the steam-chest a of a locomotive or other steam-engine, and is adapted to slide back and forth therein in the usual manner. On the upper side of this valve is a rectangular shoulder B , with which engages a yoke C . The said 25 yoke is provided with a rod D , which constitutes the valve-rod, which extends through a stuffing-box in the front end of a steam-chest, and is connected to the eccentric of an engine in the usual manner.

30 E represents a circular disk, which is arranged on the upper side of the valve, at the center thereof, and is secured on the valve by means of a pair of bolts F , the lower ends of which extend into the exhaust-cavity in the 35 lower side of the valve, and are provided with nuts G , which engage the roof of the said cavity. In the upper side of the disk E is a 40 circular opening H , in which is fitted a circular packing-disk I , which is made of cork or other suitable material. On the under side of 45 the disk E are a pair of transverse grooves K .

50 L represents a pair of flat springs, which are arranged on the upper side of the valve, and have their ends bearing upward in the ends of the groove K .

L' represents an annular ring, the interior diameter of which is equal to the diameter of

the plate or disk E , and said ring L' is slipped over the disk E and bears upon the ends of the spring K . In one side of the said ring is 55 a side or opening r , by which it is made expandable. The meeting ends of the ring on opposite sides of the slit or openings are provided with inclined grooves or openings R , in which is located a link or tongue S , which 60 serves to connect the ends of the ring. The said tongue or link is firmly secured in one of the grooves, and is free to work back and forth in the other as the ring is compressed or expanded. 65

T represents a hood, which is formed from a piece of sheet or plate metal bent in the manner shown in Fig. 4, so as to provide the supporting-plates U at its sides, which rest upon the bottom of the steam-chest and support the hood above the valve, with the ring L' , and the packing-disk I of the latter bearing against the under side of the hood. On the upper side of the hood is secured the central portion of a flat semi-elliptic spring V , the 70 ends of which bear under the top of the steam-chest, and thereby press the latter firmly downward on the annular ring and the packing-disk of the valve, so as to effect steam-tight joints therewith, and thereby prevent steam from 75 getting between the hood and ring and packing-disk, and hence serving to balance the valve and prevent excessive downward steam-pressure thereon.

80 It will be seen that by my invention the circular countersunk disk E may be readily attached to an ordinary slide-valve by planing or filing the top of the same down to a level smooth surface, parallel to the under or bearing face, and drilling the necessary holes for 85 the passage of the bolts F .

85 The operation of the device will be readily understood. The hood T is so constructed and arranged as to be subjected to the pressure of the steam contained in the valve-chamber on both its upper and under sides. The packing-ring K is forced by the action of the springs L in an upward direction against the under side of the hood, thus making a steam-tight joint and preventing access of the steam 90 to that portion of the upper side of the valve which is surrounded by the said ring, and relieving the upper side of the valve of pressure to that extent. The spring V serves to keep 95 100

the hood in place and to assist in making the steam-tight joint between said hood and the packing-ring.

Having thus described my invention, I claim—

The combination of the slide-valve, the circular countersunk disk secured on the upper side of the same, the packing-disk seated in said countersunk disk, the packing-ring surrounding the latter, the springs interposed between the circular countersunk disk and the body of the valve and having upturned ends bearing against the under side of the pack-

ing-ring, and the hood or cap having longitudinal supporting-ribs and provided on its upper side with a spring pressing against the under side of the top of the valve-chest, substantially as set forth.

In testimony that I claim the foregoing as my own I have hereto affixed my signature in presence of two witnesses.

JAMES C. ASKREN.
